Inventor:

Edward H. Lewis,

by *Charles E. Tullor*
His Attorney.

UNITED STATES PATENT OFFICE.

EDWARD H. LEWIS, OF BRIDGEPORT, CONNECTICUT, ASSIGNOR TO GENERAL ELECTRIC COMPANY, A CORPORATION OF NEW YORK.

OUTLET-BOX DEVICE.

Application filed February 17, 1928. Serial No. 255,172.

Metal outlet boxes as now constructed are generally fastened directly to the framework of a building or are mounted on a metal bar which in turn is fastened to the framework.

5 Associated with such boxes are means for attaching them to the supporting bars; studs by which the fixtures may be supported by the boxes, and hickey to facilitate the wiring operation.

10 My invention has for its object to provide a cheap, simple and relatively light device which can be used as a combined fixture stud and hickey or as a combined bar-clamp, fixture stud and hickey. More specifically my 15 invention has for its object to provide a device suitable for the above-named purposes which can be cheaply cast and which requires the minimum amount of machine work.

For a consideration of what I believe to be 20 novel and my invention, attention is directed to the accompanying description and the claims appended thereto.

In the drawing which is illustrative of 25 my invention, Fig. 1 is a view in elevation of one form of my invention, the outlet box being in section; Fig. 2 is a side view of the same; Fig. 3 is a bottom plan view of the same; Fig. 4 is a view in elevation of my improved device arranged to form a bar-clamp, 30 and Fig. 5 is an enlarged view partly in plan of my said device.

6 indicates an outlet box of any suitable construction and one which may be nailed or otherwise secured to the framework of a 35 building, either the ceiling or side wall. 7 indicates the usual knock-outs. In the center is an opening 8 through which the body of the stud 9 extends, its enlarged head 10 resting on the top surface of the box and being supported thereby. The stud is held by any 40 suitable means of which the nut 11 is an example. The stud which is suitably screw-threaded acts as a support for the fixture tube 12 leading from or associated with some form 45 of electric device such as a lamp for example. The body of the stud is made hollow, at least for the major portion of its length thereby forming a tube-like member in which the conductors 13 extending from the supply wires 50 to the current-consuming device are located.

In Fig. 4 the enlarged head of the stud is slotted to receive the bar-support 14, the latter being suitably fastened to the framework of the building. The stud is held in adjusted position on the bar by the screw 15 and

the angular position of the box on the stud once it is adjusted is retained by the nut 11.

The construction of the stud and the method of making the same will now be described in detail. Important features of a stud of the character described are that it shall be cheap to make, relatively light in weight so as to save metal, require very little machine work and afford ample space for the fixture wires. To decrease weight and save metal the body of the stud is made hollow and one portion or side thereof is gouged out or cut away longitudinally from the head through the lower end as indicated at 16, the upper end of the slot thus formed is or may be slightly enlarged so as to freely receive and afford ample space for the wires 13. The stud thus performs the function of the ordinary hickey. In order to make the stud cheaply and also afford an easy entrance for the conductors it is so shaped that it can be cast in a green sand mold and this without the use of any core whatsoever. This means that the walls defining the slot or opening 16 in the body must be separated by a space not less than the diameter of the bore of the body, and preferably the walls diverge outwardly by a slight amount from the bore to the periphery so as to facilitate drawing of the pattern from the sand. This is shown on an enlarged scale in Fig. 5 wherein the broken and dotted line 17 represents the diameter of the bore and the similar line 18 the portion of greatest divergence. It will be noted that the walls defining the slot 16 are tangential to the wall of the bore within the body and that the bore represents the most restricted area.

The exterior of the body is threaded to receive the nut 8 and also the fixture tube or support 12. The cutaway or slotted portion of the stud extends sufficiently above the tube 12 to afford ample space for the wires 13. The slot terminates at the lower end of the stud which means that the wires 13 can be inserted into it by a simple sidewise movement as distinguished from a more difficult threading movement.

When the stud is intended for use as a bar-clamp in addition to its other functions, the walls of the bar-receiving slot 19 in the head are given the same or approximately the same divergence as the walls of the bore or opening 16 to facilitate withdrawal of the pattern from the sand mold. This is clearly shown

in Fig. 5 where the stud is shown on a substantially enlarged scale and where the divergence of the side walls of the slots is exaggerated for the purpose of illustration.

5 After the casting is made it is necessary to cut the screw thread although if the thread be of coarse pitch it is quite feasible for some classes of products to form the threads in the casting operation. When intended for use 10 with the bar 14 the stud has to be tapped and threaded to receive the clamping screw 15. By using the cut-away portion there is less metal to drill and tap than if the stud were solid thereby saving in manufacturing expense 15 and permitting the use of shorter screws. Decreasing the number of machine operations means less handling of the studs. Decreasing the weight not only results in a decrease in the amount and cost of metal used 20 but also in the freight charge for these studs are shipped in large quantities.

What I claim as new and desire to secure by Letters Patent of the United States, is,—

1. A device of the character described comprising a stud having an enlarged head and a smaller body formed integral therewith, said body having a central bore, an external screw thread, and a longitudinal slot which opens into the bore to permit the introduction 25 of circuit wires into the bore, the walls defining said slot being tangential to the said

bore and diverging from the bore to the periphery of the body.

2. A device of the character described comprising a stud having an enlarged head in 35 which is formed a transverse bar-receiving slot and a tubular body formed integral with the head, said body being externally screw-threaded and having a longitudinally-extending wire-admitting slot which opens into the bore thereof, the walls of the slot diverging from said bore to the periphery thereof, and a screw located within said bore which extends through the head for clamping a supporting bar in place. 40

3. A combined fixture stud, bar-clamp and hickey which comprises a stud having an enlarged head in which is formed a transverse bar-receiving slot which is slightly divergent from one end toward the other, and a hollow body portion integral with the head which has one side cut away to form a slot, the walls of which diverge in the same direction as those of the bar-receiving slot, said body being externally screw-threaded to receive an outlet box clamping nut, and a screw which is located in the end of the body adjacent the head and which projects into the slot in the head to fasten the stud on the bar. 55

In witness whereof, I have hereunto set my hand this 10th day of February, 1928.

EDWARD H. LEWIS.
